UNITED STATES PATENT OFFICE.

JESSE W. SILVER, OF SOUTH TACOMA, WASHINGTON, ASSIGNOR OF ONE-HALF TO
CHARLES P. SAVAGE, OF TACOMA, WASHINGTON.

AEROPLANE.

1,027,572.

Specification of Letters Patent. Patented May 28, 1912.

Application filed August 8, 1910. Serial No. 576,154.

To all whom it may concern:

Be it known that I, JESSE W. SILVER, a citizen of the United States, residing at South Tacoma, in the county of Pierce and State of Washington, have invented certain new and useful Improvements in Aeroplanes; and I do declare the following to be a full, clear, and exact description of the invention, such as will enable others skilled in the art to which it appertains to make and use the same.

This invention relates to improvements in aeroplanes.

One object of the invention is to provide an aeroplane, the planes of which are pivotally connected to the frame of the car whereby the latter is supported and swings as a pendulum.

Another object is to provide an aeroplane of this character having ailerons which are automatically operated by the movement of the car frame to right the machine when the planes respond to the changing air currents.

With the foregoing and other objects in view, the invention consists of certain novel features of construction, combination and arrangement of parts as will be more fully described and particularly pointed out in the appended claims.

In the accompanying drawings: Figure 1 is a plan view of my improved aeroplane; Fig. 2 is a side view of the same; Fig. 3 is a vertical cross sectional view on the line 3-3 of Fig. 2; Fig. 4 is an enlarged vertical sectional view through the car and a portion of the supporting planes of the machine taken on a line with the propeller shaft; Fig. 5 is an enlarged vertical cross sectional view on the line 5-5 of Fig. 4; Fig. 6 is an enlarged side view of the rear end of the plane supporting frame showing the construction and arrangement of the steering plane or rudder; Fig. 7 is a vertical cross sectional view on the line 7-7 of Fig. 6; Fig. 8 is a similar view on the line 8-8 of Fig. 2.

In the embodiment of the invention I provide a car which is here shown in the form of an open frame 1 having arranged in its front end a supporting wheel 2 and on its rear end supporting wheels 3. On the frame 1 are arranged front and rear upwardly projecting pairs of standards 4 in the upper ends of which is secured a tubular shaft or sleeve 5 in which is revolvably mounted a propeller shaft 6. The rear end

of the propeller shaft 6 is also revolvably mounted in a bearing arranged on the upper ends of the rear pair of standards 4 and on the projecting rear end of the shaft 6 is fixedly mounted a propeller 7. On the shaft 6 is fixedly mounted a sprocket gear 8 which is connected by a sprocket chain 9 to a sprocket gear 10 on the shaft 11 of a suitable motor 12 which is arranged on the frame 1 as shown.

Pivottally mounted on the sleeve or tubular shaft 5 is a plane supporting frame 13 on which is arranged the upper and lower laterally extending main planes 14 and 15. The upper plane 14 is preferably continuous or projects along the entire length of the frame 13 as shown. The lower plane 15 is formed in two sections which are arranged on opposite sides of the car frame and are spaced a suitable distance below the upper plane as shown.

On the forward side of the main plane frame 13 is secured a forwardly projecting frame 16 in the outer end of which is arranged a front end or head plane 17. The frame 16 is preferably braced and secured to the car frame by an upwardly projecting supporting bar 18 the upper and lower ends of which are loosely connected with the car frame and the frame 16 to permit the independent movement of these parts. The front or head plane 17 may be adjustably mounted in the frame 16 to permit said plane to be tilted or as shown in the drawings said plane may be fixedly secured at the desired angle in the forward end of the frame 16.

To the rear side of the main plane frame is secured a rearwardly projecting tail plane frame 19 in the outer end of which is arranged upper and lower tail planes 20. Between the tail planes 20 and midway between the sides of the frame 19 is pivotally mounted a vertically disposed rudder or steering plane 21 and between the sides of the frame 19 is pivotally mounted a horizontally disposed rudder or steering plane 22 which is provided to facilitate the raising and lowering of the machine.

The vertical steering plane or rudder 21 is adapted to be swung laterally in a horizontal plane between the upper and lower tail planes 20 to steer the machine in one direction or the other and in order to operate said vertical steering plane, I provide

steering cords 23 which are connected at their rear ends to the rear end of the plane and pass therefrom through suitable guide pulleys arranged in the frames 19 and 13 5 and thence extend downwardly and are connected to the opposite ends of an operating lever 24 which is pivotally mounted intermediate its ends in one side of the car frame as shown. By thus connecting the vertical 10 plane with the lever it will be readily seen that when said lever is pushed downwardly the steering plane will be swung around in one direction and when the lever is pulled upwardly the plane will be swung around 15 in the opposite direction thereby steering the machine at the will of the operator. The horizontally disposed steering or raising and lowering plane 22 is adapted to be swung upwardly and downwardly in a vertical 20 plane to direct the upward and downward course of the machine by operating cords 25 which are connected at their outer ends to the upper and lower sides of the plane near its free edge and thence extend upwardly 25 and downwardly and are passed through suitable guide pulleys whence they extend laterally to the opposite sides of the frame 19 and around guide pulleys, thence downwardly along the opposite sides of the frame 30 19 to the forward side of the frame 13 where they are passed through guide pulleys and extend inwardly and downwardly and are connected at their lower ends to the opposite ends of an operating lever 26 which is pivotally mounted intermediate its ends on the 35 opposite side of the car frame from the lever 24. By thus connecting the horizontal steering plane with the lever 26 said plane may be tilted upwardly or downwardly by raising or lowering the lever 26 thereby providing for controlling the upward and downward movement of the machine. At a suitable position in the forward 40 portion of the car frame 13 and within convenient reach of the levers 24 and 26 is an operator's seat, said seat being here shown as being secured to the front pair of standards 4 and arranged between laterally and upwardly inclined brace bars 27 forming 45 50 part of the car frame.

The main plane frame 13 is suitably strengthened and braced by truss brace rods 28 which are secured at their opposite ends to the opposite ends of the frame 13 and are engaged with downwardly projecting truss pins arranged on the lower portion of the frame 13 as shown. In the ends of the frame 13 between the upper and lower main planes are hingedly secured ailerons 29, said 55 60 ailerons being pivotally connected at their forward edges to the supporting bars of the frame 13 thus permitting their free ends to swing upwardly or downwardly.

The ailerons are automatically operated 65 by means of a cord 30 the opposite ends of

which are secured to the lower portion of the car frame. The cord passes from the car frame to the end of the frame 13, is then carried upwardly through an opening formed in the lower plane. From thence the 70 cord passes over pulleys at the bottom and top of the frame and is carried down and attached to the free edge of the aileron at that side of the machine after which it is carried under a pulley, across the entire 75 width of the frame where it is similarly arranged and secured to the aileron on the other side of the machine and continued back to the car frame. By thus connecting the ailerons with the truck or car frame it 80 will be readily seen that if the planes or car should rock in either direction that the movement of the truck to which the ends of the aileron operating cord is attached will be imparted to the ailerons thus rocking the 85 same in the proper direction to cause the machine to quickly right itself, said ailerons thus acting automatically to maintain the equilibrium of the machine when moving in changing air currents. 90

In order to yieldingly support the main plane frame in a horizontal position on the car frame when the machine is still or on the ground, I provide a supporting spring 95 31 which is here shown and is preferably in the form of or comprises a flat resilient plate or blade 32 which is secured midway between its ends in the upper portion of the car frame and is connected at its opposite ends to the opposite bars of the main 100 plane frame by being slidably engaged in openings therein whereby the latter is yieldingly held against tilting laterally when the machine is not in flight.

From the foregoing description taken in 105 connection with the accompanying drawings, the construction and operation of the invention will be readily understood without requiring a more extended explanation.

Various changes in the form, proportion 110 and the minor details of construction may be resorted to without departing from the principle or sacrificing any of the advantages of the invention as defined in the appended claims. 115

Having thus described my invention, what I claim is:

1. An aeroplane comprising a car frame, a longitudinal sleeve secured in the upper end of the car frame, a propeller shaft revolvably mounted in said sleeve, means on the car frame for operating said shaft, a plane carrying frame pivoted on said sleeve and extending above and below the same, planes secured to the upper and lower sides 120 of said frame, a head plane frame rigid with and projecting forwardly from the said plane carrying frame, a brace extending between the car frame and the head plane frame and loosely connected to the 125 130

same, a tail plane projecting rearwardly from the main plane frame, steering planes mounted on the tail plane frame, operating levers, operating cords to connect said steering planes with said levers whereby said planes are swung in the desired direction for steering the machine, a suitably operated propeller, ailerons arranged in said main plane frame at the ends thereof, and 10 means to connect said ailerons with the car frame for joint action.

2. An aeroplane comprising a wheeled car frame, a main plane frame pivotally mounted on said car frame, main planes arranged 15 on said frame above and below the pivots thereof, a forwardly projecting head plane frame rigid with said main frame, a head plane arranged therein, a rearwardly projecting tail plane frame, upper and lower 20 tail planes arranged therein, a vertical steering plane pivotally mounted between said tail planes, a horizontal steering plane, operating levers, operating cords to connect said steering planes with said levers whereby 25 said planes are swung in the desired direction for steering the machine, a suitably operated propeller, ailerons pivoted at their forward edges between the ends of the 30 frames, and a cord to connect the rear edges of said ailerons with the bottom of the car frame, said cord being connected at its ends to the bottom of the car frame and thence to and entirely across the main frame whereby said ailerons will be automatically 35 operated when the machine is tilted.

3. An aeroplane comprising a wheeled car frame, a main plane frame pivotally mounted on said car frame, main planes arranged 40 on said frame, a forwardly projecting head plane, a rearwardly projecting tail plane frame, upper and lower tail planes arranged therein, a vertical steering plane pivotally mounted between said tail planes, 45 a horizontal steering plane, operating levers, operating cords to connect said steering planes with said levers, whereby said planes are swung in the desired direction for steering the machine, a suitably operated propeller, ailerons arranged in said main plane frame at the ends of the same, and means 50 to connect said ailerons with the car frame whereby said ailerons will be automatically operated when the machine is tilted.

4. An aeroplane comprising a car frame, 55 a longitudinal sleeve secured in the upper end of the car frame, a propeller shaft revolvably mounted in said sleeve, means on the car frame for operating said shaft, a plane carrying frame pivoted on said sleeve and 60 extending above and below the same, planes secured to the upper and lower sides of said frame, a head plane frame rigid with and projecting forwardly from the said plane carrying frame, a brace extending 65 between the car frame and the head plane frame and loosely connected to the same, steering devices mounted on the plane carrying frame, and means on the car frame to operate said devices. 70

5. An aeroplane comprising a wheeled car frame, a main plane frame pivotally mounted on said car frame, main planes arranged 75 on said frame, above and below the pivots thereof, a forwardly projecting head plane frame rigid with said main frame, a head plane arranged therein, a rearwardly projecting tail plane frame, upper and lower tail planes arranged therein, a vertical steering plane pivotally mounted between said 80 tail planes, a horizontal steering plane, operating levers, operating cords to connect said steering planes with said levers whereby said planes are swung in the desired direction for steering the machine, a suitably 85 operated propeller, ailerons arranged in said main plane frame at the ends of the same, and means to connect said ailerons with the car frame whereby said ailerons will be automatically 90 operated when the machine is tilted.

6. In an aeroplane, a car frame, a plane frame pivotally mounted on the car frame and comprising bars having openings therein, and a plate spring centrally secured in 95 the car frame and having its ends slightly engaged in the openings in the frame bars for yieldingly maintaining the normal relative positions of the car frame and plane frame. 100

In testimony whereof I have hereunto set my hand in presence of two subscribing witnesses.
